INVENTOR,
George E. Marlatt

UNITED STATES PATENT OFFICE

GEORGE E. MARLATT, OF PASADENA, CALIFORNIA

TYPOGRAPHICAL SLUG-CASTING MACHINE

Application filed June 8, 1931. Serial No. 542,798.

In typographical slug-casting machines of the kind to which this invention relates, the slugs are cast in a mold which is commonly made adjustable to produce slugs of different lengths and thickness. The slugs are forced from the mold and thence between a pair of trimming knives in advance of an ejector blade. Having passed the trimming knives, the slugs are further advanced by the ejector blade to a position from which they slide by gravity through a chute to a receiving galley. The improvements to be described are directed to a better control of the slugs after they have passed the trimming knives and after they are beyond control of the ejector blade. In the description, reference is made to the accompanying drawings, in which:

Figure 1 is a right-hand perspective view of a portion of a typographical slug-casting machine of the linotype class, having the present invention applied thereto, the parts thereof being shown in inactive position;

Fig. 1^a shows in left-hand perspective that part of the spacer-driver mechanism immediately associated with this invention;

Fig. 2 is a perspective view similar to a portion of Fig. 1, with the parts in the positions they occupy just before a slug is delivered to the galley in which the slugs are accumulated, and showing a slug in front of the slug-ejector blade and about to pass beyond control of the blade;

Fig. 3 shows in perspective a slug of recessed type in position for comparison with the slug of solid type shown in Fig. 2;

Fig. 4 shows in side elevation a slug-guiding plate as reversed from its position in Fig. 2 and elsewhere, and as redesigned for present purposes;

Fig. 5 shows in horizontal cross-section the slug-guiding plate of Fig. 4 in its relation to the slug-trimming knives and the fixed or left-hand wall of the slug channel;

Fig. 6 is a perspective view showing the manner in which the movable slug-trimming knife and the movable slug-delivery-chute wall are commonly interconnected for adjustment in unison as controlled by the handle appearing at the right of Fig. 1; this view

also shows the manner of dividing the slug-receiving galley to receive short slugs in connection with the present improvements; it shows also a modification of a portion of the present invention;

Fig. 7 is an exploded view showing certain parts appearing in Fig. 6, and the manner of their assembly;

Fig. 7^a shows the construction of certain parts appearing in Figs. 6 and 7;

Fig. 8 is a side elevation showing in dotted lines successive positions of a slug being delivered from the casting mold to the slug-delivery chute leading to the slug-accumulating galley, and, in full lines, illustrates a slug in abnormal position in connection with prior-art construction;

Fig. 9 shows a slug of the recessed type, in position for comparison with the slug of different type appearing in Fig. 8;

Fig. 10 is a left-hand perspective view of the galley supporting bracket shown in right-hand perspective in the principal views of the drawings, illustrating its special construction in connection with the present improvements;

Fig. 11 is a perspective view with the parts in the positions they occupy after a slug has been delivered to the galley; this view also shows a modified form of a feature of the present invention;

Fig. 12 is a perspective view of a portion of the slug-accumulating galley with the galley-dividing bar applied as in Fig. 6 but with the parts in the positions they occupy when the galley is filled with slugs.

In the drawings well-known elements are identified by reference letters as follows: the liners A, B between which the slugs are cast; the ejector blades C; the left-hand or fixed slug-trimming knife D; the right-hand or adjustable trimming knife E; the slug-supporting floor F; the left-hand or fixed wall G of the slug-delivery channel; the right-hand or adjustable wall H of the slug-delivery channel, hereinafter called the spring plate or spring-pressed plate; the spring I which controls said spring plate; the floor J of the slug-delivery chute; the left-hand or fixed wall K of said chute; the right-hand

or adjustable wall L of said chute; the slide-block M which interconnects the adjustable wall (L) with the adjustable knife (E) for unitary movement; the knife-block handle 5 N which controls the adjustment of said knife and said wall through said slide (M); the slug-accumulating galley O; the friction-slide P on said galley; the left-hand bracket Q on which the galley rests; the right-hand bracket R on which the galley rests and which also forms the left-hand wall (A) and floor support of the slug-delivery chute; the slug-accumulating lever or slug lever S; the slide-rod T through which the 10 slug lever is actuated in right-hand direction; the slug-lever roll a which actuates the slide (T), the justification or spacer driving rod e, the driving block i thereon, and the justification-rod lever o; the spring U which actuates 15 the slug lever in left-hand direction; the machine frame V known as the vice frame, which forms the left-hand wall (G) of the slug-delivery channel, supports the galley brackets (Q—R), the slug lever (S), its actuating rod (T), the slug-delivery-channel floor (F), the 20 slug-trimming knives (D—E), the knife block W as a whole, and the matrix transporter or well-known first-elevator Z of linotype machines. Solid slugs are designated by X, 25 and recessed slugs by Y. The ensuing description will indicate to what extent certain of the aforementioned elements are modified in construction for present purposes. The 30 ejector-blade and knife block units selected for illustration are intended to be merely examples of any of several systems serving the 35 same purposes.

In the prior-art construction, one difficulty arises from the fact that while the slugs 40 X—Y (Fig. 8) may be varied in length by half-ems of measurement, the ejector blades C vary only by two-em measurements, the result being that the slugs must at times be ejected and advanced by a blade which is as 45 much as one and one-half ems shorter than the slug; in fact, the slugs in all lengths are somewhat shorter than the accompanying ejector blade, due to points 1 of the mold-liners A—B projecting into the mold casting-slot. In order that the slugs may be trimmed to accurate thicknesses, they are cast with ribs 50 3 spaced two ems or one-third of an inch apart on one of their sides, and if the slug is of such length that the final rib thereon is 55 beyond reach of the longest blade which may be used in connection with the slug, the final rib will act as a fulcrum and cause the slug to turn and take on abnormal, angular position in front of the ejector blade. This results from the fact that the slugs must be resisted in their advance between a wall G on their smooth side and a spring-pressed resistance plate H¹ (Fig. 8) on their ribbed side, in order that they will not tumble forward 60 and will be held accurately in front of

the ejector blade while being moved in advance thereof on the floor F of the slug-delivery channel. In the case of short slugs especially, the usual spring plate H¹ exerts more pressure on the final rib than on the other ribs of the slug, due to the fact that the plate is loosely hinged to the adjustable knife E and to the fact that the plate spring I is centrally banked with its two ends pressing against the plate. The plate will therefore 70 tilt on the last rib of slugs which are less than half of maximum length, and will do so on longer slugs such as illustrated in Fig. 8 if the upper half of the spring is stronger than its lower half, or if the plate hinges 2 are 75 not accurately fitted, or if the plate is warped. Hence from one cause or another, or from a combination of causes, slugs which have a rib (3 in Fig. 8) beyond the reach of the longest 80 ejector blade permissible in use therewith are liable to turn to the position of the slug shown in full lines in Fig. 8, and when this occurs the slug either remains suspended between the spring plate I and its opposing wall G or it may be improperly delivered to the chute 85 floor J instead of being properly delivered as indicated in dotted lines in Fig. 8. As a remedy for this improper behavior of the slugs, I provide the spring plate H with clearances for the ribs on the slugs. These clearances may extend either entirely or part way across the spring plate as grooves 4. In Figs. 4 and 5 they are shown as grooves 4 of receding depth since an increasing clearance 37 beyond the trimming edges of the knives D, E 90 results in a sidewise freedom of the slugs at the point where the spring plate I meets the trimming knife E, so that nothing would be gained by extending the grooves 4 to the rear edge of the plate and the plate will be less liable to warp if the grooves are tapered and shortened as shown. At their forward ends the grooves 4 are cut through the plate as notches 5 so that individual resultant tongues 6 may be bent to relieve the pressure on the 95 final rib of slugs Y (Fig. 3) of the recessed type on which the ribs are variously spaced apart. For example, in Fig. 9 the final rib 7 does not correspond in position with any rib on the solid type of slug X on which all the 100 ribs except the first one occur in half-em positions, following even-em positions on the slug, while on the recessed slugs illustrated a rib occurs in the 15½-em position. On the 105 recessed slugs the ribs are usually broader than are those on the solid slugs, and it is therefore a matter of choice whether the grooves 4 in the plate I shall be made wide enough to also accommodate the ribs on recessed slugs. It will be seen, however, that 110 in the case of all slugs having ribs intended to enter the grooves 4, the slugs will be locked in proper position by reason of the ribs 7 between the plate grooves entering between the 115 ribs 3 on the slugs, and in addition, since the 120

space between the ribs on the slugs is much wider than the ribs 3 themselves, the plate ribs 7 and tongues 6 are less liable than the narrow ribs on the slugs to act as fulcrum surfaces causing improper turning of the slugs; also, the body of the slugs between the ribs 3 is more uniformly accurate than are the ribs 3, since accuracy of the ribs 3 is dependent on the degree of accuracy with which the trimming knives are sharpened and adjusted; for example, if the right-hand trimming knife is not accurately ground, certain ribs will be thicker than others and only the thick ribs will touch the friction plate, so that a thin rib which happens to be the last one covered by the ejector blade will have no effect to relieve the pressure on a thick rib which is beyond the reach of the ejector blade. However, the slight discrepancy between thick and thin ribs will not prevent both from co-operating with the grooves 4 to prevent turning of the slugs.

If properly controlled as provided for by the afore described improvement, the slugs will move forward on the horizontal floor F and will drop precipitously therefrom to the position illustrated in dotted lines in Fig. 8, and be turned on the chute floor J from their horizontal position to the face-up position they occupy in the gallery O. But in order that the slugs may thus move from the chute floor J it is necessary that the floor J be kept polished and lubricated, since it becomes coated with lead from the repeated dropping of the slugs thereon, and especially so at the upper portion thereof which receives the impact of the slugs. Heretofore it has been customary to polish the chute floor manually, the floor being removable for the purpose. Since this must sometimes be done several times daily for best results and since the leaded condition continues until polishing becomes imperative, it is a source of considerable annoyance to keyboard operators. I therefore provide for lubricating the chute floor J with ease and without removal, and for doing so automatically, if desired, each time a slug is delivered. For this purpose the slanted portion of the left-hand or fixed chute wall K is separated from the chute floor support R, leaving a space 8 (Fig. 10) beneath the wall to accommodate the floor strip J, which is widened accordingly. The floor strip is also widened to the right and a portion 9 thereof is bent downwardly and provided with openings to engage slide pins 10 secured in the galley bracket R. Behind the depending portion 9 the bracket R has a bore 11 to accommodate a spring 12 which forces the floor strip outwardly when permitted to do so. For automatic actuation of the floor strip, the slug-accumulating lever S is provided with a hinged finger 13 which may be thrown into position to engage the floor strip and force it to the left against resistance of

the spring 12 each time the slug lever is pulled to the left by its spring U. When the slug lever retreats as controlled in usual manner through the slide-rod T, the spring 12 forces the floor strip to the right (Fig. 2), the extent of its movement being determined by the expanded length of the spring 12, which holds the floor strip in its lubricated position except when it is forced to the left either as described or manually. To prevent unnecessary lubrication, the hinged finger 13 may be thrown back as shown in dotted lines in Fig. 2, and the floor strip may then be actuated manually if conditions are such that only very occasional lubrication is required. For the purpose of supplying the lubricant, the chute wall K has a longitudinal opening 14 which may be packed with a lubricant-saturated material, such as felt, resting on or pressing against the floor strip J. Each time the floor strip is moved to the left as described, that portion thereof which is the path for the slugs will be forced beneath the lubrication chamber 14 and will be returned in a lubricated condition by the spring 12.

A modified construction for imparting movement from the slug lever to the chute floor J is shown in Fig. 6. This construction has the advantage that it does not involve any change in the usual slug lever S¹. The bracket R is provided with a lug 15 as a bearing for the angular end 16 of an end-pivoted lever 17 the central portion 18 of which bears against the depending portion 9 of the chute floor J, the spring 12 being employed as afore described. The free end of the lever 17 is bent to an angle 19 on which is mounted a dog 20 having a depending portion 21 fitting behind the lever 17 when the device is in use, thus rendering the lever 17 and dog 20 in effect one continuous lever to be acted upon at its forward end by the slug lever S¹ when the slug lever moves to the left. The device is thrown out of use by raising the dog 20 on its bearing 19 and then dropping it with its depending portion 21 in front of the lever 17, so that when the dog is contacted by the slug lever it will not be effective to move the floor-actuating lever 17.

Another modified form of the chute-floor lubricating means is illustrated in Fig. 11. In this construction the left-hand chute wall 38 has the lubrication chamber 14 as before described, but that portion of the chute wall which covers the floor strip J¹ is rendered movable relative to the floor strip, the strip being held in fixed position as by means of a hinge-pin 39, to be explained. Slide pins 40—41 are secured to the movable wall 38 at opposite ends thereof and bear in lugs 42—43, respectively, projecting from the galley bracket R. The upper slide-pin 40 has fixed thereto a head 44 between which and the lug 42 is interposed a spring 45 which serves to hold the wall 38 in its normal position against

the lugs 42—43. If the spring is compressed, as by pressing on the head 44, the wall 38 is thereby caused to move over the surface of the plate J^1 and thus lubricate this floor of the chute. A slide rod 46 bears in the bracket R and has a return bend 47 which engages the head 44. The forward end of the rod 46 is threaded and carries a nut 48 which may be adjusted to engage or disengage the forked end of a centrally-pivoted lever 49 the lower end of which rests behind the slug lever S¹. In the drawings the device is shown inoperative by reason of the nut 48 being adjusted away from the lever 49. If the nut be adjusted until resisted by the lever 49 as stopped against the slug lever, any additional turning of the nut will then draw the rod 46 to the right, compressing the spring 45 and moving the wall 38 to its lubricating position. With the parts in such position, movement of the slug lever to the right to permit entry of a slug, will free the centrally-pivoted lever 49 and the spring 45 will force the wall 38 to normal position, leaving the floor J^1 lubricated and permitting the entry of the following slug. The rod 46 and head 44 may be disengaged by moving these members in relatively opposite directions, to the left and right respectively, and when so disengaged, if the movable wall 38 be forced to the right to clear the fixed wall K, incidentally clearing the lower slide pin 41 from its bearing 43, the movable wall may then be turned upwardly, thus providing access to the whole surface of the chute floor J^1 for thorough cleaning and polishing.

The slug having been turned from the vertical position by the slope of the chute, it slides into the galley O where, together with the accumulated slugs X, it is pushed to the left by the slug-lever S, thus providing room for a following slug to slide into the galley. The aforementioned spring U serves to pull the slug lever S to the left, and the power means (Fig. 1^a) acting against the slide-rod T forces the lever to the right following each slug delivery, all in well known manner. Since the slugs vary in thickness, length and weight, the result has been that the slope of the galley O proves ideal for the delivery of only certain slugs, heavy slugs arriving in their stopped position with unnecessary force while lighter slugs frequently fail to slide to their final position. To partially check the momentum of heavy slugs, it is customary to slant the face of the slug lever so that it is not quite parallel with the friction slide P which serves as a retaining wall for the slugs. The result has been that since only the lower end of the face of the slug lever is depended upon to move the slugs to the left, the slugs may remain parallel with the slanted face 22 of the lever instead of being delivered parallel with the face 23 of the retaining wall, and will therefore frequently remain

in a position interfering with the movement of a following slug into the galley. A slug in such interfering position is shown in dotted lines in Fig. 2. Such a condition becomes a source of annoyance to the keyboard operator, since it interferes seriously with the production of slugs. To remedy the defect, I provide the slug lever with a movable face plate 24 which automatically adjusts itself to increased or decreased steepness according to the thickness of the slugs being produced, and which will also adjust itself parallel with the retaining wall 23 each time a slug is moved forward in the galley. This face plate 24 is wedge shaped to provide a normal slant which may be somewhat greater than the slant of the usual face 22 aforescribed. Near its lower end the movable-face member is provided with a shoulder 25 which serves as a fulcrum point about which the member may rock to vary its angularity. A spring 26 engages the movable member just above the fulcrum point and similarly engages the slug lever S at its upper end, being held in tension by means of a tension pin 27. This spring will at all times hold the shoulder 25 against the slug lever, and when the slug lever is in normal position (Fig. 1) or between advanced and retracted positions, the spring will hold the movable member against the fixed face 22 of the slug lever throughout the length of the contacting face thereof. To prevent the member 24 from working down on the angular end of the spring 26, it is provided with a stud 35 (Fig. 7) midway of the depth of its shoulder 25, and the usual face 24 of the slug lever has a recess 36 (Fig. 6) in which the stud may move freely with the member 24 but will prevent the member from working down on the spring or from working up and carrying the spring with it. As thus constructed, the device may be readily applied to machines outstanding in commercial use. The right-hand wall L of the slug-delivery chute and the right-hand slug-trimming knife E are interconnected by means of a slide block M (Fig. 6), rendering these members adjustable in unison according to the thickness of the slugs being produced. In the form of construction selected for illustration this adjustment is made by means of a handle N (Fig. 1), movement of which from one to another position will vary the space between the trimming knives and between the walls K—L of the chute. The movable face 24 of the slug lever is made to overreach the end of the chute wall L, so that when the slug lever is retracted (Fig. 2) the member 24 will contact and be stopped against the wall L, thus decreasing the slant of the movable face 24 an extreme amount when thin slugs are being produced, and increasing the slant correspondingly as the wall L is adjusted to the right to accommodate thicker slugs. In connection with slugs

of maximum thickness, the movable face will contact the adjustable wall without being rocked, thus providing a maximum slant to check the momentum of the heaviest slugs. In Fig. 2 this extreme adjustment is shown in dotted lines. Since the slug-lever S moves a fixed distance in both directions regardless of the varying thicknesses of slugs, the result heretofore has been that too much room was provided for the entry of thin slugs in front of the lever face 22 and not enough room for entry of the thickest slugs. In the present disclosure, this condition is corrected since the stopping of the member 24 against the member L reduces the entry space for thin slugs, while the increased slant of the lever face provided by the member 24 increases the mouth of the entry space for slugs of maximum thickness. A slug having been delivered to the galley, the slug lever is pulled to the left by its spring U, and as the lower end of the movable face 24 strikes the newly-deposited slug, the member 24 is thereby caused to rock about its shoulder 25 and take a position parallel with the retaining wall 23, thus leaving the slug in a corresponding position and providing ample room for the entry of a following slug. (See Fig. 2.) The slug shown in dotted lines in the galley O of Fig. 2 may be supposed to have been displaced manually to show the position it might retain in the absence of the improved slug-lever. In its dotted-line position it would interfere with entry into the galley of the slug shown in front of the ejector blade. If it were a longer slug and its upper end had failed to pass the lower end of the inner chute-wall K because of a leaded condition of the chute, the consequence would be a bending of the slug from the impact of the upper end of the slug lever.

When short slugs are being produced, it is customary to employ a galley-dividing bar 28 (Figs. 6 and 12) which stops the slugs midway of the width of the galley. In order that such a bar may be employed in connection with the improved slug-accumulator described above, I provide the movable-face member 24 with a clearance-opening 29 to accommodate the end of the slug-stopping bar 28. The end of the bar is made of reduced size to suit the clearance, the object being attained by providing a tongue 30 hinged in a block 31 rigidly secured in the angle of the dividing bar. In order that the tongue 30 may extend across the path of the incoming slugs, the slug-lever is provided with a clearance recess 32 to accommodate the end of the tongue 30. In order that the movable face 24 may be actuated to keep the short slugs parallel with the retaining wall, the friction slide P which is employed in connection with long slugs is left in its normal starting position and is there held against the shoulder of the afore-described

block 31. With the lower slide P thus held against movement, the lower end of the movable face 24 will strike the lower slide P each time the slug lever advances, and consequently slugs stopped against the dividing bar 70 will be properly aligned with the face of the upper slide P¹. The galley-dividing bar 28 may be secured in usual manner to the galley, by means of a button-latch 34. As thus constructed the dividing bar and upper slide P¹ 75 may be placed and removed without disturbing the lower slide P, which remains in position for use in connection with long slugs. However, with the present improvement in use, short slugs may also be accumulated 80 in the lower position on the galley, since the continuous lubrication of their channel and the ideal slant of the slug-lever face overcomes the conditions which have heretofore made the use of the dividing bar necessary. Such being the case, I provide for doubling the capacity of the galley when short slugs are being cast. For this purpose, the tongue 30 is hinged in a recess 50 of the block 31 and clears through 85 a slot 51 in the end of the dividing bar 28. Assuming that the upper division of the galley has been first filled with slugs, the lower friction slide P is moved to clear the block 90 31 and slugs equaling in thickness the block 95 31 are then removed from their position on the tongue 30 and placed in the position vacated by the lower friction slide P. The tongue 30 may then be swung up as shown 100 in dotted lines in Fig. 7, and thereafter slugs 105 will slide to the lower position on the galley, and the galley contents need not be dumped until both positions are filled or until the work in hand is finished if it totals less than 110 two full galley lengths.

Heretofore the friction slides P—P¹ have been permitted to drop from the end of the galley when the galley is nearly filled with slugs, thus notifying the keyboard operator to guard against overfilling the galley and so causing slugs to spill from the left end thereof. A positive stop for the slugs has been avoided since crowding the slugs against such a stop would jeopardize the security of the galley on its brackets, the galley being held merely by a flush stud 52 in the left-hand bracket Q, so that the galley may be quickly placed and removed. Owing to an endwise slant of the galley intended to cause the slugs to lean against the retaining wall P, there is liability of slugs dropping from the end of the galley with the slide P, or thereafter if an operator misjudges the remaining space at the end of the galley or inadvertently presses the column of slugs 115 from the right-hand end thereof. To remedy this condition, I provide as follows: For the upper division of the galley, the dividing bar 28 carries a slide-rod 53 held in the angle 120 of the bar by means of a fixed block 54. The 125

rod has a shoulder 55 to limit its movement to the left. This shoulder also results in an offset which prevents the rod from turning in one direction, and in the opposite direction 5 a similar purpose is served by an angular right end 56 on the rod. At its left end the rod is provided with a return bend 57 for engagement with an eye 58 shaped from the friction spring 59 which holds the slide P¹ 10 on the slug-supporting bar. As the friction slide P¹ is advanced toward the left end of the galley, the eye 58 engages the return bend 57 and causes the slide-rod 53 to move from its position in Fig. 6 to its position in 15 Fig. 12. When the slide P¹ has cleared the end of the galley, it will drop and be stopped against the lower portion of the slide-rod as shown in connection with the lower slide P in Fig. 12. This dropping of the slides 20 P—P¹ will serve to notify an operator that the galley is entirely filled, and the galley having been dumped, movement of the slide P or P¹ back to its starting position will cause the slide-rod to be returned by reason of contact of the eye 58 with the angular end 56 of 25 the slide-rod. In connection with the lower division of the galley, the slide rod 60 rests in the clearance resulting from the corner bead 61 of the galley, and a slot 62 through the 30 bead 61 permits the angle portion of the slide-rod to be positioned outside the galley. Movement of the slide rod to the left is limited by contact of the angle 63 with the end of the slot 62. The slide-rod is kept from 35 turning by means of a keeper wire 64 secured in the bead 61, the angular end 63 of the slide-rod fitting between the keeper wire and the flange 66 of the galley. The keeper wire may be dispensed with if the return bend 67 40 (Fig. 12) of the slide-rod is made long enough to remain in constant engagement with the eye 58. In use, both the upper 53 and lower 60 slide-rods function alike and as described. The slide-rods are stopped in 45 their movement to the left when the friction slides P—P¹ have just cleared the galley, hence the galley may be entirely filled without risk of the slugs spilling therefrom.

Having described my invention, its construction, and the manner of its use, what I claim as new and desire to secure by Letters Patent of the United States, is:

1. In a slug-casting machine, in combination with the ribbed slugs, the adjustable 55 knife for trimming the ribs of said slugs, the slug-ejector blade, and the spring plate for guiding said slugs from said trimming knife in advance of said ejector blade, grooves in said spring plate coinciding in 60 position with the ribs on said slugs and capable of engaging said ribs and thus preventing abnormal behavior of the slugs while passing said spring plate in advance of said ejector blade.

35 2. A combination as specified in claim 1,

characterized by the fact that the grooves in the recited spring plate decrease in depth from front to rear ends thereof.

3. A combination as specified in claim 1, characterized by the fact that the grooves in 70 the recited spring plate are cut through said plate at the front edge thereof to form alternating tongues and notches, said tongues being capable of engaging the body of the recited slugs and said notches providing clear- 75 ances for the ribs thereon.

4. In a slug-casting machine, in combination with the adjustable slug-trimming knife, slugs having ribs to be trimmed by 80 said knife, and the spring plate for guiding the slugs away from said knife, alternating tongues and notches in the front edge of said spring plate, said tongues being capable of entering between the ribs of the slugs and said notches permitting such entry. 85

5. In a slug-casting machine, in combination with the horizontal slug-delivery channel, the slug chute leading from said channel, the slug-receiving galley to which said chute leads, and a floor for said chute a side 90 wall for said chute having in connection therewith means for holding a lubricant, said side wall and said floor being relatively movable for the purpose of lubricating said floor from said lubricant-holding means. 95

6. A combination as specified in claim 5, including also means for imparting relative movement to the recited chute floor and side wall automatically from a periodically-actuated machine element. 100

7. In a slug-casting machine, in combination with the horizontal slug-delivery channel, the slug chute leading from said channel, and the slug-receiving galley to which said chute leads, a side wall and a movable floor for said chute, said side wall having lubricant-holding means in connection therewith, and said floor being movable beneath said side wall to receive lubrication therefrom. 110

8. A combination as recited in claim 7, including also means for imparting movement to the recited chute floor from a periodically-actuated machine element. 115

9. In a slug-casting machine, in combination with the horizontal slug-delivery channel, the slug chute leading from said channel and the slug-receiving galley to which said chute leads, a floor and a movable side wall for said chute, said floor extending beneath said side wall, and said side wall having lubricant-holding means in connection therewith and in contact with said floor, whereby movement of said wall will cause said floor to be lubricated. 120

10. A combination as specified in claim 9, including also means for imparting movement to the recited movable wall from a periodically-actuated machine element. 125

11. In a slug-casting machine, in combina- 130

tion with the horizontal slug-delivery channel, the slug chute leading therefrom, the slug-receiving galley to which said chute leads, a floor for said chute and a side wall therefor, means whereby said side wall may be raised and lowered at will in order to provide access to said floor for cleaning and polishing purposes.

12. In a slug-casting machine, in combination with the slug-receiving galley, the friction slug-retaining wall thereon, and the slug lever for moving the slugs towards and with said retaining wall, a fulcrumed plate on the face of said slug lever and extending across the length thereof opposite said retaining wall, said plate when inactive being slanted relative to said retaining wall, and being capable of rocking about its fulcrum point to a position parallel with said retaining wall when its lower end contacts a slug newly received in said galley, thereby causing said newly-received slug to be deposited parallel with said retaining wall.

13. A combination as specified in claim 12, characterized by the fact that the recited fulcrumed plate has an opening therethrough, that the face of the recited slug lever has a recess in register with said opening, and including a galley-dividing bar having an end tongue clearing through said opening and into said recess, for stopping short slugs in position to be advanced on said galley dividing bar against a friction slug-retaining wall thereon, and means locked to the galley against which means the lower end of the fulcrumed plate may strike to cause the upper end thereof to move parallel with the retaining wall on said dividing bar, thereby causing short slugs to be deposited parallel with said retaining wall.

14. In a slug-casting machine, in combination with the slug-delivery chute, the adjustable side wall thereof, the slug-receiving galley, and the slug lever for advancing slugs in said galley, a fulcrumed plate on the slug-advancing face of said slug lever, said plate overreaching the end of said adjustable wall and being stopped thereby at different angles according to the adjustment of said wall, thus varying the angularity of said plate according to the thickness of slugs being delivered through said chute to said galley.

15. In a slug-casting machine, in combination with the slug-receiving galley and the galley-dividing bar thereon, means whereby the slug-stopping end of said bar may be moved to permit the slugs to pass beyond said bar to a lower slug-receiving position.

16. In a slug-casting machine, in combination with the slug-receiving galley and the slug-retaining slide thereon, means whereby the slug-retaining slide may clear the end of the galley-floor and drop therefrom while remaining attached to the galley in a position

preventing the spilling of the slugs therefrom.

Signed at Pasadena, Los Angeles County, California, this 20th day of January, 1931.

GEORGE E. MARLATT.
